US00D973398S

(12) **United States Design Patent** (10) **Patent No.:** **US D973,398 S**
(45) **Date of Patent:** **** Dec. 27, 2022**

(54) **TABLE**

(71) Applicant: **New-Tec Integration (Xiamen) Co., Ltd.**, Xiamen (CN)

(72) Inventor: **Luhao Leng**, Xiamen (CN)

(73) Assignee: **New-Tec Integration (Xiamen) Co., Ltd.**, Xiamen (CN)

(**) Term: **15 Years**

(21) Appl. No.: **29/719,864**

(22) Filed: **Jan. 8, 2020**

(30) **Foreign Application Priority Data**

Jul. 15, 2019 (CN) 201930375451.7

(51) **LOC (13) Cl.** **06-03**

(57) **CLAIM**

The ornamental design for a table, as shown and described.

DESCRIPTION

FIG. 1 is a front elevation view of a table showing the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof; and,

FIG. 8 is a perspective view of the table shown in a collapsed orientation.

The broken lines shown in the drawings are for the purpose of illustrating portions of the article and form no part of the claimed design.

1 Claim, 8 Drawing Sheets
